(57) **CLAIM**

The ornamental design for a bottle for eyelash extension glue, as shown and described.

DESCRIPTION

FIG. 1 is a left-side, top perspective view of a bottle for eyelash extension glue showing my new design.

FIG. 2 is a front view of my new design shown in FIG. 1.

FIG. 3 is a rear view of my new design shown in FIG. 1.

FIG. 4 is a left-side view of my new design shown in FIG. 1.

FIG. 5 is a right-side view of my new design shown in FIG. 1.

FIG. 6 is a top view of my new design shown in FIG. 1.

FIG. 7 is a bottom view of my new design shown in FIG. 1.

FIG. 8 is a left-side, top perspective view of my new design shown in FIG. 1 with the cap removed.

FIG. 9 is a front view of my new design shown in FIG. 1 with the cap removed.

FIG. 10 is a rear view of my new design shown in FIG. 1 with the cap removed.

FIG. 11 is a left-side view of my new design shown in FIG. 1 with the cap removed.

FIG. 12 is a right-side view of my new design shown in FIG. 1 with the cap removed.

FIG. 13 is a top view of my new design shown in FIG. 1 with the cap removed; and,

FIG. 14 is a bottom view of my new design shown in FIG. 1 with the cap removed.

Broken lines in the drawings depict portions of the bottle that form no part of the claimed design.

1 Claim, 14 Drawing Sheets
